J. F. PHILLIPPI,

BLACKBOARD.

APPLICATION FILED APR. 6, 1922.

1,437,193.

Patented Nov. 28, 1922.

J.F. Phillippi,
Inventor

By *Chambers* Attorney

UNITED STATES PATENT OFFICE.

JOSEPH F. PHILLIPPI, OF HAMBURG, NEW YORK.

BLACKBOARD.

Application filed April 6, 1922. Serial No. 550,066.

To all whom it may concern:

Be it known that I, JOSEPH F. PHILLIPPI, a citizen of the United States, residing at Hamburg, in the county of Erie and State 5 of New York, have invented a new and useful Blackboard, of which the following is a specification.

This invention relates to educational appliances and more particularly to black- 10 boards.

The object of the invention is to provide a rotatable blackboard in connection with a screen or curtain having an opening for use to expose indicia carried by the board, the 15 turning of the board operating to bring into view different figures or characters dependent upon the subject being demon- strated.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed may be made within the scope of what is claimed without departing from the spirit of the invention.

In the accompanying drawings:—

30 Figure 1 represents a side elevation of the board constituting this invention, and

Fig. 2 is a front elevation thereof.

In the embodiment illustrated a supporting structure is shown in the form of a 35 standard or post 1 composed of telescopically engaged sections 2 and 3 held in adjusted position by a set screw 4 which also extends through a collar 5 carried by section 1 from which a laterally extending arm 6 projects 40 with a chalk tray 7 mounted at the outer end of said arm.

The standard 1 is mounted in a base 8 which may be of any desired configuration being here shown cylindrical and provided 45 with radially extending feet 9 any desired number of which may be employed, three being here shown.

The post section 3 is provided at its upper end with a T-shaped coupling 10 in 50 which is mounted a substantially U-shaped bracket 11 having bearings 12 and 13 at the free ends thereof in which is supported a

spindle 14. This spindle 14 extends through these bearings and has fixed to one end a demonstrating member here shown in the 55 form of a circular blackboard 15. The other end of the spindle or shaft 14 has a handle 16 for rotating the spindle and the board 15 carried thereby. A rod 17 rises from the bearing 13 and has a cross bar or head 18 60 secured to its upper end and extending laterally beyond opposite sides thereof. Shade brackets 19 are carried by the cross bar 18 and are designed to support the spring roller 20 having a curtain 21 secured thereto. This 65 curtain 21 is mounted in front of the board 15 and has a slot-like opening 22 therein preferably midway its width positioned so as to disclose indicia carried by the outer face of the board 15 as is shown clearly in 70 Fig. 2.

The rotary board 15 may carry on its outer face any suitable indicia according to the subject to be demonstrated, digits 23 being here shown, which are designed to be 75 used in teaching children addition, subtraction and the like. It is of course understood that other subjects may be demonstrated such as geometry, geography and the like, the characters being displayed through 80 the opening 22 in the curtain 21 and said opening may be lengthened or shortened as desired by raising or lowering the curtain in front of the board in the same manner that a spring shade roller is operated. 85

By forming the standard 1 of telescopically engaged sections, the board 15 may be raised or lowered to suit the convenience of the teacher, and is held adjusted by the set screw 4 in an obvious manner. 90

I claim:—

1. In a device of the class described a supporting structure a horizontally disposed shaft mounted to rotate therein, an upright blackboard carried by one end of said shaft 95 and rotatable therewith, and a vertically adjusted screen arranged in front of said board and having a sight opening therein.

2. In a device of the class described a supporting structure comprising a standard 100 having supporting feet and composed of telescopically engaged sections, a U-shaped bracket carried by one of said sections, a shaft rotatably mounted in the arms of said

bracket, a blackboard fixed to said shaft to rotate therewith the standard rising from said structure at the rear of said board, a spring roller screen mounted on said stand 5 ard in advance of said board and having a sight opening therein adapted to display the front face of the board.

In testimony that I claim the foregoing as my own, I have hereto affixed my signature in the presence of two witnesses.

JOSEPH F. PHILLIPPI.
